(57) CLAIM

I claim the ornamental design for a garment, as shown and described.

DESCRIPTION

FIG. 1 is a front view of a garment, showing my new design; FIG. 2 is a rear view thereof.

The areas shaded with stippling in FIGS. 1 and 2 are indicative of the difference in color and/or texture with respect to the non-shaded areas of the design.

The dashed line showing in FIG. 1 represents stitching or a surface treatment resembling to stitching.
